UNITED STATES PATENT OFFICE.

PATRICK L. HUSSEY, OF DAYTON, OHIO.

DESIGN FOR A BICYCLE CRANK-HANGER.

SPECIFICATION forming part of Design No. 29,246, dated August 16, 1898.

Application filed July 18, 1898. Serial No. 686,296. Term of patent 7 years.

To all whom it may concern:

Be it known that I, PATRICK L. HUSSEY, a citizen of the United States, residing at Dayton, in the county of Montgomery and State of Ohio, have invented and produced a new and original Design for Bicycle Crank-Hangers; and I do declare the following to be a full, clear, and exact description of the same, reference being had to the accompanying drawings, forming a part thereof.

Figure 1 is a side elevation of a bicycle crank-hanger, showing my new design. Fig. 2 is a front or rear elevation of the same.

As shown in the drawings, the leading or material feature of my design consists in the body of the crank-hanger having a substantially rounded or oval shape, with three tubular extensions projecting therefrom on one side of the horizontal center thereof.

The body A of the crank-hanger is uniformly bulged or rounded and terminates on

each side in annular flanges B, which surround circular openings C in each side.

D designates tubular lugs or extensions projecting from the rounded surface of said crank-hanger and the annular walls of which slant inwardly from their base. These tubular extensions occupy substantially one-half of the rounded surface of the crank-hanger and are equidistant between the annular flanges B B.

Having described my invention, I claim as new and desire to secure by Letters Patent—

The design for a bicycle crank-hanger, as herein shown and described.

In testimony whereof I hereunto affix my signature in the presence of two witnesses.

PATRICK L. HUSSEY.
